ATTORNEYS.

UNITED STATES PATENT OFFICE.

DANIEL W. BLACKWELL, OF SAN DIEGO, CALIFORNIA.

CATCH.

Application filed March 26, 1921. Serial No. 455,729.

To all whom it may concern:

Be it known that DANIEL W. BLACKWELL, a citizen of the United States, residing at San Diego, in the county of San Diego and State of California, has invented a certain new and useful Catch, of which the following is a specification.

My invention relates to catches more particularly adapted for use in connection with door closures but adapted for use in connection with any stationary member and movable member where they come adjacent to each other, and the objects of my invention are: First, to provide a novelly constructed catch for supporting a movable object relatively to a stationary one, but which may be readily moved by sufficient force; Second, to provide a catch of this class which is positive in its action; Third, to provide a catch of this class, in which the movable object will be easily moved into position but more force required to move it in the opposite direction; Fourth, to provide a catch of this class whereby either one of the members may be mounted on either the movable or stationary object; Fifth, to provide a catch of this class, which is very simple, economical of construction, durable, easy to operate, easy to install, positive in its action and which will not readily deteriorate or get out of order.

With these and other objects in view as will appear hereinafter, my invention consists of certain novel features of construction, combination and arrangement of parts and portions, as will be hereinafter described in detail and particularly set forth in the appended claims, reference being had to the accompanying drawings and to the characters of reference thereon which form a part of this application, in which:

Figure 1, is a longitudinal sectional view of the operative assembly parts of the catch; Fig. 2, a sectional view on the line 2—2 of Fig. 1; Fig. 3, a front elevational view of the operative assembly parts of the catch; Fig. 4, is a sectional view through 4—4 of the stationary plate; Fig. 5, is an edge view of said plate; and Fig. 6, a side elevational view thereof.

Similar characters of reference refer to the similar parts and portions throughout the several views of the drawings.

The casing 1, casing head 2, revoluble latch member 3, supporting pin 4, spring 5,

spring supporting member 6, and the plate 7, constitute the principal parts and portions of my catch.

The casing 1, is a cylindrical member, open at its one end at 1^a, and provided with a turned inner end portion 1^b, adapted for the seat of the large end of the spring 5. This casing 1 is provided in opposite sides with inwardly extended integral portions 1^c, which are adapted for stops for the revoluble member 3. Secured in the front end of this cylindrical member 1, is the head member 2, which is secured therein by beading the end of this member 1, over the member 2, the member 2, being provided with an off set portion at the edge, so that the member 2 is flush with the outer edge of the member 1, as shown best in Figs. 1 and 2 of the drawings. This member 2 is provided with a slot extending across the same.

Pivottally mounted in this casing 1, upon the pin 4, to which it is secured is a revoluble catch member 3, it being noted that the pin 4, is provided with journaled ends in the casing 1, which is provided with inwardly extending portions so that the ends of the pin will not engage the object when the casing is inserted. The revoluble member 3, is provided with two extended lug portions 3^a and 3^b, which are adapted to extend out through the notch 2^a in the member 2, when the member 3 is turned in certain position. This revoluble member 3 is also provided with another lug 3^c opposite to the lugs 3^a and 3^b. This lug 3^c it will be noted is set over the center from between the lug 3^a and 3^b on the opposite side to provide more pressure on the revoluble member by turning on one side of the center more than on the other side, so that when closing the object, less pressure is required than when opening the object.

Pivottally mounted in the lug 3^c is the member 6, which is a one piece member and provided with an enlarged portion then reduced over which the small end of the conical shaped spring 5, is mounted, the other end of this member 6, extending through the spring and is free for movement in either direction, the conical shaped spring permitting such movement. It will be noted that this conical spring 5 is a compression spring and in connection with the member 6 serves to support the revoluble member 3 against revolution in either direction on either side of the center, dependent

upon the position of said revoluble member. Secured on the face of the other closure member is a plate 7 which is provided with an inwardly depressed portion 7^a, which is 5 adapted to permit the movement of the lug 3^a over said depressed portion and permit said lug to engage the edge of the plate contiguous to said depressed portion revolving the member 3 about its axis. When this 10 member 3 is revolved to a certain position the lug 3^b of the member 3 will enter a hole 7^b in the plate 7, holding the members 3 and 7 in a certain relative position to each other until released by a force sufficient to over- 15 come the spring 5.

It will be noted that the plate 7 may either be mounted on the stationary or movable member and that the casing 1 together with its assembled parts may be mounted in the 20 other part but it is preferred to mount the casing 1 in the stationary part and the plate 7 on the movable part.

Though I have shown and described a particular construction, combination and arrangement of parts and portions I do not wish to be limited to this particular construction, combination and arrangement, but desire to include in the purview of my invention the construction, combination and arrangement substantially as set forth in the appended claims.

It is obvious that with this construction there is provided a catch device in which one member is mounted in one portion and the other member on the other portion, that the plate 7 is provided with a double notch and is adapted to receive one of the lugs 3^b and turn the member 3 a partial revolution compressing the spring 5. That by movement when in such position, this spring must again be compressed to move it over the center therefore providing a retarding medium for the movable member relatively to the stationary member. The members 1^c of the 35 casing 1 providing stops for the revoluble member on the opposite sides. That the position of lug 3^c relative to the lugs 3^b and 3^a will determine the relative amount of pres- 40

sure required for moving the revoluble member in opposite direction. 50

Having thus described my invention what I claim as new and desire to secure by Letters Patent is:

1. A device of the class described, including a plate provided with spaced apart recesses secured to one member, a casing secured to the opposite member, a revoluble member in said casing provided with spaced apart lugs on its edge adapted to extend past the face of said casing and enter said recesses in said plate and a conical spring means for controlling and retarding the movement of said revoluble member. 55

2. A device of the class described including a plate provided with spaced apart recesses secured to one member, a casing secured to the opposite member, a revoluble member in said casing provided with spaced apart lugs on its edge adapted to extend past the face of said casing and enter said recesses in said plate and with another lug on the opposite side of said revoluble member, a spring supporting member with one end pivotally mounted in said last mentioned lug and a spring means for controlling the 70 movement of said spring supporting member. 75

3. A catch of the class described including, a plate provided with spaced apart recesses, a casing, a revoluble member in said casing provided with spaced apart lugs adapted to enter said recesses in said plate and provided with another lug positioned on the opposite side of said revoluble member closer to one of said lugs than to the other, a spring supporting member pivotally mounted in said last mentioned lug and a conical shaped spring with its apex engaging said spring supporting member whereby said spring supporting member has free movement in 80 the base of said conical shaped spring. 85

In testimony whereof, I have hereunto set my hand at San Diego, California, this 19th day of March, 1921.

DANIEL W. BLACKWELL.
